METHOD OF AND MEANS FOR VARYING RADIO FREQUENCY CURRENTS

Mendel Osnos, Berlin, Germany, assignor to Tele-funken Gesellschaft für Drahtlose Telegraphie m. b. H., Berlin, Germany, a corporation of Germany

Application June 14, 1929, Serial No. 370,826
In Germany June 25, 1928

5 Claims. (Cl. 250—36)

It is known from practice that radio transmission on very short waves is often attended by what is known as fading. It has often been observed that occasionally a very slight change 5 or variation in the wave-length is sufficient to insure satisfactory communication. With this end in view the suggestion has been made to alter the frequency of the outgoing wave periodically, say, several thousand times per second, 10 with the result that part of the energy which happens to be at the frequency most favorable at the time during such alterations in wave-length will reach the receiving station at the rhythm of such alternating current, in a manner 15 free from fading, so that telephonic or telegraphic communication is made possible. This rhythm variation in the wave-length artificially produced in the said manner is known as "wobbling".

20 However, a technical difficulty arises insofar as the requisite slight change in the wave-length or frequency during wobbling must be exactly maintained within definite limits.

Now, in the present invention ways and means 25 are disclosed whereby wobbling or frequency variation is effected in a simple manner and with sufficient accuracy for the elimination of fading. The scheme may also be used to good advantage in systems utilizing frequency modulation.

30 The underlying idea of the invention consists in that in the circuit which controls the frequency of the tube to be controlled (say, in its grid circuit), one or more crystals are combined with one or more tubes whose impedance is altered at the rhythm or rate of the desired wobbling frequency by the aid of a suitable auxiliary alternating potential.

A number of embodiments of the basic idea of the invention are diagrammatically shown by 40 way of example in Figures 1 to 7 of the accompanying drawing.

Referring to Figure 1, *a* is the tube to be controlled, *l* and *r* denote the inductances and ohmic resistances connected between its filament *f* and its grid *g*. *k* is a grid crystal, and *x* an impedance, inductive, or capacitive in series with said crystal. In parallel relation with said resistance is a thermionic tube *b* either with or without a grid. Through an inductance *L* which offers a 50 high impedance for the radio frequency current of tube *g* or of its grid circuit, the tube *b* is supplied with an auxiliary alternating current potential *e* being of the desired wobbling frequency. The resistance of tube *b* changes markedly at 55 the rate of the frequency of potential *e*, and thus

causes, at the rhythm of the same frequency, corresponding changes in the grid frequency of tube *g*, and in this manner the desired wobbling is produced.

In the scheme shown in Figure 2, a second crystal *k1* is connected in parallel to crystal *k*. It is not absolutely necessary to provide a parallel impedance *x* in this case. But it is suitable to so choose crystals *k* and *k1* that their natural waves will differ slightly from each other. This scheme offers the advantage that the amplitude of the radio frequency waves generated by tube *a* may be kept substantially constant in spite of the frequency changes occasioned by wobbling.

In the circuit arrangement hereinbefore described, only every other half-wave of potential *e* is used for wobbling (control), owing to the unilateral action of valve tube *b*. In order to utilize both halves of the wave of potential *e*, the variable tube resistance acted upon by potential *e* may consist of two oppositely connected tubes *b* and *b1*, as shown in Figure 3. One half of potential *e* acts upon the resistance of tube *b* and the next half influences the resistance of tube *b1*. While the auxiliary potential *e* is still low, the two tubes *b* and *b1* act as stoppers, and the oscillation frequency of tube *a* or its grid circuit is substantially determined and governed by crystal *k1*. But when potential *e* during either half of the cycle exceeds a definite value, then either tube *b* or tube *b1* will become permeable for the current, according to the direction of potential *e*, and crystal *k* becomes operative, so that during these intervals of time the radio frequency of the tube *a* is governed by the two crystals *k* and *k1*.

A similar circuit scheme adapted to utilize both half-waves of the control potential *e* is shown in Figure 4. Also in this instance, the two tubes *b*, *b1*, are connected in opposition. The control potential *e* is supplied by way of the primary winding of a transformer *t* whose secondary is included between the cathode of tube *b* and the anode of tube *b1*, its middle being connected with the grid circuit of tube *a* or if desired, with the grounding terminal.

If also the branch of the second crystal *k1* is to be directly controlled by a tube resistance, arrangements, for instance, could be chosen in a way as illustrated in Figure 5. Also here the two tube resistances subjected to the control by the auxiliary alternating current potential *e* are disposed in opposition, though in such a manner that crystal *k1* is now in series with tube *b1*. The two inductances *L* being permeable for the wob-

bling frequency, while impermeable for the radio frequency of tube *a* or its grid circuit separate the poles of the two crystals connected with the corresponding valve tubes. In this scheme, the 5 radio frequency of tube *a* is essentially governed alternately, according to the direction of potential *e* by either of the two crystals.

Connecting the crystals in series, then the tube 10 impedances controlling them must be connected in parallel thereto as shown, e. g., in Figure 6, instead of being connected in series therewith as in the preceding embodiment. The crystal belonging to a given tube will then be disconnected or be cut in circuit, according to whether the 15 respective tube is permeable or impermeable for the current.

If the tubes *b* and *b*₁ comprised in all of the circuit schemes hereinbefore described are furnished with grids, then the auxiliary potential 20 *e* provided to influence their resistance could be applied also to the grid instead of to the plate. In this instance, an arrangement as illustrated, for instance, in Figure 3, would have to be modified to result in a scheme of the kind illustrated in 25 Figure 7, or else the two tubes *b* and *b*₁ could be connected in the same sense, while the direction of coupling of the grid transformer in one of these tubes would have to be reversed.

I claim as my invention:

- 30 1. Means for producing oscillations of a constant amplitude and of a frequency which varies between fixed limits comprising, a thermionic oscillation generator having input electrodes, a frequency determining circuit comprising parallelly connected crystals connected between said input electrodes, a variable impedance in series with each of said crystals, and means for varying said impedance oppositely and continuously at a super-audible rate.
- 40 2. Means for producing oscillations of a constant amplitude and of a frequency which varies between fixed limits comprising, a thermionic oscillation generator having input electrodes, a plurality of crystals of different frequencies connected between said input electrodes, circuits for connecting the internal impedance of a separate thermionic device with each of said crystals, and means for varying alternately the conductivity of said thermionic devices.
- 50 3. An oscillation generator comprising, a thermionic tube having input electrodes, a plurality

of crystals of different frequencies, each having a terminal connected to one of said input electrodes, a plurality of thermionic discharge devices, means for connecting opposed terminals of said devices together and to the other of said input electrodes, means for connecting the free terminals of each of said thermionic discharge devices to the other electrode of a different one of said crystals, and means for applying alternating current potentials continuously to the electrodes in 10 said thermionic discharge devices.

4. In combination, an electron discharge device oscillator having a control electrode and cathode, 15 said oscillator being adapted to produce oscillations, and means for determining the frequency 15 of the oscillations produced and for shifting the same between two frequencies as a limit comprising, a pair of piezo-electric crystals, one of said crystals having a frequency equal to the frequency 20 of the upper limit of said frequencies between 20 which the oscillations are to be shifted, the other of said crystals having a frequency equal to the frequency of the lower limit between which said oscillations are to be shifted, a circuit connecting one terminal of each of said crystals to the control grid of said device, unilateral impedances connecting the other terminals of said crystals to the cathode of said device, said impedances being 25 of opposed polarity, and means for varying the values of said impedances alternately to thereby 30 shift the control of said oscillations from one of said crystals to the other, thereby shifting the frequency of the oscillations produced.

5. An oscillation generator comprising, a thermionic tube having a control grid and a cathode, 35 a plurality of piezo-electric crystals of different natural frequencies, each crystal having two electrodes, a connection between one electrode of each crystal and said control grid, an additional thermionic tube having two electrodes, a connection 40 between the other electrode of one of said crystals and one electrode of said additional tube, a connection between the other electrode of said additional tube and the cathode of said first named tube, a connection between the other electrode of the other of said crystals and the cathode of said first named tube, and means for varying 45 the impedance between the electrodes of said additional tube at a modulating frequency rate.

MENDEL OSNOS.
